COMBINED CONTROL AND DISPLAY MODULE FOR AN AUTOMATED CHEMISTRY APPARATUS

Henry E. Amar, Bronxville, N.Y., Herman G. Diebler,
North Haledon, N.J., and Jack Isreeli, Mamaroneck,
George Payne, Bedford Hills, and William J. Smythe,
Tarrytown, N.Y., assignors to Technicon Instruments
Corporation, Tarrytown, N.Y.

Filed June 9, 1972, Ser. No. 261,560

Term of patent 14 years

Int. Cl. D24—01

U.S. Cl. D16—2 C

FIG. 1

FIG. 2

FIG. 3

FIG. 4

FIG. 5

FIG. 1 is a front perspective view of a combined control and display module for an automated chemistry apparatus.

FIG. 2 is a front elevational view of the module shown in FIG. 1;

FIG. 3 is a top plan view of the module;

FIG. 4 is an elevational view of the side of the module not seen in FIG. 1; and

FIG. 5 is a rear elevational view of the module.

We claim:

The ornamental design for a combined control and display module for an automated chemistry apparatus, substantially as illustrated.
